UNITED STATES PATENT OFFICE.

JOHN M. FERRISS, OF NEW YORK, N. Y., ASSIGNOR TO THE HARRIMAN NATIONAL BANK, OF NEW YORK, N. Y.

HAND DUPLICATOR OR STAMP.

Substitute for application Serial No. 9,909, filed February 18, 1925. This application filed June 18, 1926.
Serial No. 117,001.

This invention relates to an improved hand duplicator or stamp of the type in which a stencil on which reading matter of any kind is cut by a stylus or on a typewriter machine, is used in conjunction with an inking device and means for positioning and holding the various parts in an efficient manner.

This application is refiled for my abandoned application, Serial No. 9,909, filed February 18th, 1925.

I am familiar with the various patents that have been issued on devices of this nature and also with the constructions that have been marketed, and have endeavored in my new structure to overcome the objections and defects hitherto encountered and produce an article that is simple and economical in construction, easy to assemble and handle, cleanly and not apt to leak or drip its ink, and capable of locking the stencil sheet and ink pad tightly in position to prevent creeping thereof in use, and the consequent smearing and smudging of the work.

I have also been able in my device, to increase the area of the actual printing surface and at the same time reduce the weight of the parts, without enlarging the outside measurements defining the space occupied by the structure as a whole.

I have also devised a new form of lid or top cover which effectively acts as a closure and locking member to hold in close immovable engagement the various components after they have been assembled and are ready for use.

Other advantages and a detailed description of the foregoing are set forth in the following specification and illustrated in the drawings in which:

Fig. 1 is a side view of the device.

Fig. 2 is a sectional view on the line 2—2 of Fig. 3.

Fig. 3 is an end view of the device.

Fig. 4 is a sectional view on the line 4—4 of Fig. 1.

Fig. 5 is a detailed plan view of the locking corner.

Fig. 6 is a detailed plan view of the hinge corner.

Fig. 7 is a detail view of the cover and handle.

Fig. 8 is an enlarged fragmentary sectional view showing the details of the construction. 55

Fig. 9 is a detail view of the ink pad.

Fig. 10 is a detail view of the stencil sheet.

The diaphragm A is provided with a 60 curved perforated bottom wall 10, across which the ink pad C and the stencil sheet D are positioned, side walls 11—11, end walls 13—13, and inturned rectangular flanges 14—14 on the upper edges of the end 65 walls 13—13, the perforations in the bottom wall being indicated by the reference numeral 12.

To position and securely hold the ink pad C and the stencil sheet D on the diaphragm 70 A, two rows of bosses 27—27 and 28—28 are arranged on the upper exterior portions of the side walls 11—11, the bosses 27 engaging with the slots 39—39 in the re-inforcing strips 38—38 at either end of the ink 75 pad C, and the bosses 28 engaging with the slots 40—40 in the said reinforcing strip and also with the slots 43—43 in the reinforcing strip 42 on the stencil sheet D, the opposite end 41 of the said sheet being left free so 80 that it can be rolled onto the diaphragm to secure a smooth engagement with the ink pad.

To hold the lock the said pad and stencil sheet on the bosses 27 and 28 after they are 85 positioned thereon, pad clamps 15—15 hinged at 17—17 to the portion 23 of one of the end walls 13, and stencil clamps 16—16 hinged in a like manner at 18—18 are provided. The pad clamps 15 are L 90 shaped with horizontal top walls and vertical side walls having slots 29—29 for engagement with the bosses 27—27 after the ink pad C has been seated thereon by engagement with the slots 39. At their free ends 95 the hinged pad clamps 15 are bent at right angles to form spring catches 24—24 with finger grips 19—19, having apertures 21—21 to engage with lugs 26—26 projecting from the end wall 13 of the diaphragm A.

In a similar manner the stencil clamps 16—16 are hinged at 18—18 and are provided with the slots 30—30 for engagement with the bosses 28—28 after the ink pad C and the stencil sheet D have been seated on 100 the bosses 27 and 28. The spring catches on 105

clamps 16—16 are indicated at 25—25, the finger grips at 20—20, and the apertures for the lugs 26—26 at 22—22.

The horizontal top walls of the pad clamps 15—15 extend inwardly to form an ink tight closure with the upper edges of the ink pad C which extend above the line of the bosses 27—27, the longitudinal edges of the lid B and the longitudinal upper edges of the side walls 11—11 of the diaphragm A.

The horizontal top flanges of the stencil clamps 16—16 extend outwardly to form a guide or register against which the material on which the printing is to be done 15 may be positioned to secure perfect alignment with what is cut on the stencil sheet.

This construction as described in the foregoing has many advantages. The stencil sheets in a device of this kind are constantly 20 changed for the production of new matter, but an ink pad lasts a considerable time and it is therefore desirable that the removal of a stencil be easy of accomplishment without a consequential disturbance of the ink 25 pad. In this construction, to put on a new stencil sheet it is only necessary to open the stencil clamps 16, and remove the stencil sheet D from the bosses 28, and then replace the new stencil sheet on the said bosses 30 28, during all of which the ink pad claims 16—15 remain in closed position locking the said pad on the bosses 27. As the ink for the pad is supplied by removing the lid B from the top of the device and depositing the said 35 ink in the interior of the diaphragm A, where it reaches the pad through the perforations 12 it is obvious that when the pad clamps 15 are opened up to permit the removal of the lid B, the ink pad C will be 40 locked on the bosses 28 by the stencil clamps 16 which need not be opened for the re-inking operation.

The closure lid B with a handle 31 secured at 34, consists of an arch spring member 45 constructed of a suitable metal and formed so that when the lower edges of the arch are positioned on the flanges 14—14 of the end walls 13—13 of the diaphragm a slight downward pressure will serve to flatten the 50 arch and move the said lower edges laterally along the flanges 14—14 and under the inturned flanges constituting the upper horizontal walls of the pad clamps 15—15, where the whole lid member is locked 55 against movement of any kind by the engagement of the lugs 34—34 in the apertures 33—33 in the spring latches 32—32 on the member 23 of the diaphragm A.

To further provide against any leakage or 60 dripping of ink from the interior of the diaphragm, gaskets or sealing strips 35—35 of felt or a similar material are located on the under side of the ends of the lid B whereby when the said lid is flattened and locked in

position as shown in Fig. 3, an ink tight 65 closure results.

To aid the operator of this device in its use, an indicator or register showing where the cut lines on the stencil sheet are located, and where they will appear on the printed 70 sheet, and comprising a series of grooves 36—36 are cut in the lower portion of the end wall of the diaphragm A as shown in Fig. 3.

In Fig. 9 the details of the inking pad C 75 25 are disclosed, 37 indicating the body portion of the pad, with reinforcing strips 38—38 at either end, outer perforations 39—39 for engagement with the bosses 27—27 and inner perforations 40—40 for engagement 80 with the bosses 28—28 on the diaphragm A.

In Fig. 10 the stencil sheet D is shown in detail, 41 indicating the free end, 42 is the reinforced end and 43—43 are the perforations for engagement with the bosses 28—28 85 on the diaphragm A.

It should be noted that the diaphragm A is provided with the bosses 28—28 on both of its side walls 11—11 so that the stencil sheet D could be secured thereto on either 90 side as desired, the free end of the sheet being rolled into position and clamped on the bosses on the opposite side by the clamping member 16.

The rows of bosses 28—28 are provided on 95 both side walls of the diaphragm A for engagement with the slots 40—40 in the inking pad C and also to permit of the stencil sheet D being locked on the said bosses 28—28 on either one of the side walls of the 100 diaphragm through engagement by the said bosses 28—28 with the slots 43—43 in the stencil sheet D. As is obvious, the said stencil sheet D could be made with the reinforcing strip 42 at both ends if desired in which 105 case the two ends of the stencil could be locked in engagement with the two sets of bosses 28—28 on either of the side walls of the diaphragm A.

As is obvious, I have obtained in the device disclosed in the foregoing description a structure that is light in weight, compact in size, attractive in appearance, and easy of operation.

I do not desire to limit myself strictly to the preferred embodiment disclosed herein as there are a number of other ways in which the construction could be used without departing from the spirit and scope of my invention.

I claim:

1. In a duplicator the combination of the following elements; a diaphragm; an ink pad; a stencil sheet; pad clamping members; stencil clamping members; and a spring lid 125 adapted to lock together the said diaphragm, ink pad, and pad clamping members.

2. In a duplicator the combination of the

- following elements; a perforated diaphragm provided on its side walls with a plurality of bosses and on the upper surfaces of its end walls with inturned rectangular flanges; 5 an ink pad; a stencil sheet; pad clamping members; stencil clamping members; and a spring lid adapted to lock together the said diaphragm, ink pad, and pad clamping members.
- 10 3. In a duplicator the combination of the following elements; a diaphragm; an ink pad provided at either end with reinforcing members having a plurality of slots therein; a stencil sheet; pad clamping members; stencil clamping members; and a spring lid adapted to lock together the said diaphragm, ink pad, and pad clamping members.
- 15 4. In a duplicator the combination of the following elements; a diaphragm; an ink pad; a stencil sheet having one free end and one end provided with a reinforcing member having a plurality of slots therein; pad clamping members; stencil clamping members; and a spring lid adapted to lock 20 together the said diaphragm, ink pad, and pad clamping members.
- 25 5. In a duplicator the combination of the following elements; a diaphragm provided on its side walls with a plurality of bosses; an ink pad; a stencil sheet; pad and stencil clamping members hingedly mounted on the said diaphragm and provided with slots adapted to engage with the bosses on the side walls of the diaphragm; and a spring 30 lid adapted to lock together the said diaphragm, ink pad, and pad clamping members.
- 35 6. In a duplicator the combination of the following elements; a diaphragm; an ink pad; a stencil sheet; means adapted to clamp 40
- the said ink pad on the diaphragm; and means independent of the said pad clamps for clamping the stencil sheet on the said diaphragm; and a spring lid adapted to lock together the said diaphragm, ink pad, 45 and pad clamping members.
7. In a duplicator the combination of the following elements; a perforated diaphragm provided on its side walls with a plurality of bosses and on its end walls with inwardly extending rectangular flanges; an ink pad comprising a body member of absorbent material having reinforcements at either end provided with a plurality of slots adapted to engage with the bosses on the diaphragm; a stencil sheet comprising a body member having one free end, and a reinforced opposite end provided with a plurality of slots adapted to engage with the bosses on the diaphragm; ink pad clamping 50 members hingedly mounted at one end on one end wall of the said diaphragm and adapted to be detachably locked at their opposite ends upon the other end wall of the said diaphragm, and provided with slots 55 adapted to engage with the bosses on the side walls of the diaphragm; stencil clamping members hingedly mounted at one end on one end wall of the said diaphragm and adapted to be detachably locked at their opposite ends upon the other end wall of the said diaphragm and provided with slots 60 adapted to engage with the bosses on the side walls of the diaphragm; and a closure member comprising an arched spring lid 65 adapted to be positioned above and upon the said diaphragm and to lock together the said diaphragm, ink pad, and pad clamping members.
- 70 75
